CARRIAGE DRIVE POWER CONTROL

Walter T. Sagner, West Hartford, Conn., assignor
to Underwood Corporation, New York, N. Y., a
corporation of Delaware

Application December 28, 1950, Serial No. 203,068

12 Claims. (Cl. 197—66)

1

This invention relates to mechanisms in typewriters or other office machines for returning a carriage by motor power, and more particularly pertains to devices for controlling a motor return drive to obtain carriage return runs to accurate predetermined positions.

In typewriting machines the carriage must be power-returned reliably to settle in the exact letter-feed position corresponding to the beginning of a new writing line. In most conventional constructions the disabling of the power-return mechanism entails the opening of a drive clutch against considerable opposition, and also the return movement through the final space is not only too short to assure sufficient clutch opening movement, but if the carriage return run is short, the carriage also moves with too little momentum to furnish a reliably active clutch opening force. In machines having a fine letter-feed pitch, the difficulty is accentuated because the clutch opening action must ensue in a very small movement of the carriage if the carriage is to settle in the exact desired letter-feed position. Entering into the problem is also the yield and necessary working play in the mechanism for transmitting opening action to the drive clutch.

For effecting more reliably carriage return terminations it has become known to employ power devices called into operation at the end of power returns, but such devices have been of complex nature or they operated harshly, and in some cases a power-actuated carriage return draw band served to impart the clutch opening motion and for this was subjected to increased strain and wear.

Towards overcoming the stated difficulties and deficiencies present in prior devices, it is an object of the invention to provide simple, accurately and reliably effective means employing motor power to disable a carriage return mechanism responsive to the carriage reaching the desired return position.

A further object of the invention is to provide efficient power return means for a carriage, including a reliably controlled easily active mechanism operating at the conclusion of each return run under power supplied by the power return drive.

It is a more specific object of the invention to provide in connection with power return mechanism embodying a carriage return draw band, efficient, easily active means to disable the power return mechanism by a straightening action of said draw band, reliably controlled to ensue at the arrival of the carriage in the return

2

position while subjecting the draw band and other mechanism to a minimum of strain, wear and shock.

It is also an object of the invention to provide in association with a normally disabled power return drive for a carriage, efficient control devices whereby such return drive is enabled under power of a spring responsive to a tripping action and whereby the drive is opened efficiently responsive to arrival of the carriage in return position by power action automatically and reliably supplied at the proper time by the carriage return drive.

In conjunction with all the above stated objects it is a further object to provide for efficient line spacing of a paper supporting device provided on the carriage, and as an initial event in each activation of the power carriage return means before any power return movement of the carriage commences.

Many other objects and features of the invention will be apparent upon consideration of the detailed description which follows, as such description is read in the light of the accompanying drawings, but it is to be understood that the invention is capable of embodiment other than that specifically described.

General reference is had to the power return mechanism shown in the patent to Helmond, No. 2,262,676, dated November 11, 1941, over which the present invention is an improvement.

Referring to the drawings:

Figure 1 is a front sectional elevation illustrating a power return drive for a typewriter carriage, and controlling mechanism for said return drive, all in normal, idle condition.

Figure 2 is a fragmentary front perspective view of a line spacing device which is the same as in said patent and which is provided at the left end of the typewriter carriage.

Figure 3 is a front elevation similar to Figure 1 but the power return mechanism for the carriage is in the process of being disabled by the motor power as a result of the carriage having reached return position, and

Figure 4 is a side elevation of a carriage return enabling trip mechanism including a schematically represented carriage return key lever.

Referring now more particularly to Figure 1, a fragmentarily illustrated typewriter carriage is designated by the numeral 19 and includes a left and a right carriage end 11 rising from a usual rail 12, the latter being guided in a conventional manner between a front trackway 13

and a rear trackway 16 for letter feed and return travel. Said trackways 13 and 14 are part of a framework of the machine which also includes a right side wall 15 and a usual housing 16 at the middle of the rear portion of the machine supporting conventional tabulating and other mechanism. The carriage 10 includes extending lengthwise thereof at the rear a bar 17 supporting a line-end margin stop 18 and a return limiting margin stop 19.

A carriage feed spring, not shown, urges the carriage 10 in letter-feed direction leftwardly and a usual letter-feed escapement, also not shown, is in control over the carriage as in conventional typewriters. The normal opposite range of line travel of the carriage is established by the two margin stops 18 and 19 in conjunction with counterstop means which in the structure shown may be regarded to comprise in upright counterstop arm 20, and another arm 21 the purpose of which will be explained later, both said arms 20 and 21 rising from below the housing through the perforation 22 provided in a top plate 23 of the housing 16. The counterstop arm 20 has at its lower end a slot 20a for mounting it on a frame-supported pin 28. Spring means 28b urge and hold the counterstop arm 20 upwardly to the limit established by the lower end of the slot 20a and rightwardly to the limit of the perforation 22 in the top plate 23. Towards the end of typing a line, the line-end margin stop 18 engages and displaces the counterstop arm 20 leftwardly in the perforation 22. In turn the stop arm 28 operates a lever indicated at 29 of a conventional line-end lock mechanism for the typing instrumentalities which may be in the form shown in the patent to Yaeger, No. 2,362,229, dated November 7, 1944. If after the line-end lock mechanism becomes effective it is desired to type beyond the margin, there is operated a usual line-end lock releasing mechanism which acts on the counterstop arm 20 to move it downwardly below the range of both margin stops and of which only a lever 29a for downward action on a pin of the arm 20 is shown.

The other arm 21 of the counterstop means stands normally at the left limit in the perforation 22 and reaches downwardly along the counterstop arm 20 for pivotal support thereon at 21a.

The return drive for the carriage is the same as in the stated patent to Helmond and comprises a gear 24 and a clutch member 25 fast on a shaft 26, the gear 24, and therefore the clutch member 25, being continuously motor driven while the machine is in use. Adjacent the clutch member 25 on the shaft 26, but normally separated therefrom and thus not turning, is another clutch member 27 as seen in Figure 1. The clutch members 25 and 27 have clutch teeth which face axially of the shaft 26 towards each other and are normally separated. The clutch member 27 is in the form of a sleeve loosely mounted on the shaft and has an annular groove 30 for accommodation of a conventional clutch closing fork 31. A carriage return draw band drum 32 is freely rotatable on the shaft 26 but axially stationary. The clutch member 27 is connected with drum 32 for axial shift relative thereto and rotation therewith by provision of splines 33 which extend from said clutch member 27 into perforations in the draw band drum 32. Under constant urge of a light clock-type spring 34 contained in a shell 35, the drum 32 keeps a draw band extending therefrom to a

line spacing mechanism 39 on the carriage, under constant light tension to take up slack. The clutch controlling fork 31 is part of a rocking structure including also an arm 37, and this rocking structure, by means of a fairly strong spring 38, seen in Figures 1 and 3, is constantly urged clockwise to urge engagement of the clutch member 27 with the clutch member 25. Normally, however, as seen in Figure 1, the rocking structure 37, 31 is held in an open clutch position by a control arm 40 which has pivotal support on the frame as at 41 and has a link connection 42 with the arm 37, the said control arm as shown in Figure 4 being normally retained by a latch 43 against upward, clutch closing movement.

The draw band 36 leads from the winding drum 32 upwardly over an idler sheave 44 and from there leftwardly in a bend around the underside of a pulley 45, first over an idler pulley 46 and then over an idler pulley 47 and finally onto a small drum 48 which is rotatively supported on the left carriage end 11 and comprises a part of the aforesaid line spacing device 39. Referring to Figure 2 the line spacing device comprises further a bevel pinion 50 unitarily rotatable with the drum 48 and meshing with a bevel gear sector 51 which is pivotally supported on the carriage as at 52. Said sector 51 has integral therewith a cam 53 on which there bears a follower roll 54. Said follower roll 54 is on a usual spring-restored lever 55 which carries a line space pawl 56 for line-feeding engagement with a usual toothed line space wheel 57, the latter being fast on a platen shaft 58. A spring 60 is strong enough relatively to the draw band winding spring 34 to cause the sector 51 normally to occupy the position seen in Figure 2 wherein a part of the sector engages a stop pin 61. In such normal position of the sector 51 some of the draw band 36 is wound on the drum 48, it being understood that an end of the draw band has an anchorage on such drum. Whenever the carriage return drive is rendered active in a manner to be explained hereinafter, the draw band before picking up the carriage will turn the drum 48 of the line spacing device 39, for the cam 53 to act on the roller 54 and to cause a line spacing operation. The movement of the sector is limited by engagement of a pin 62 with a part of the carriage end, and following such engagement the draw band 36 picks up the carriage 10 and moves it in return direction.

The pulley 45 about which the draw band is led in a bend is mounted on an arm 66 of a carriage return shut-off lever which is pivoted at 69 and includes another arm 67 having a roller 68 for carriage return shut-off descent on the arm 40 which has connection with the clutch control fork 31. A spring 70 having connection with the arm 66 is strong enough with respect to the draw band winding spring 34 to cause the lever to rest normally in a clockwise direction against a pin 72.

The carriage return drive clutch 25, 27 is closeable under control of a carriage return key schematically represented at 75 in Figure 4 to cause a line-spacing operation followed by a return motion of the carriage to the limit afforded by the carriage return stop 19. If the carriage is already in the returned position there will nevertheless follow the line-spacing operation a fractional space return movement of the carriage, the carriage falling back into the proper position under control of the escapement as the drive becomes inactive. The carriage return key

75 has a pin 76 for displacing the latch 43 rearwardly clear of the clutch control arm 40. When the arm 40 is so freed the spring 38 will cause the fork 31 to move the clutch member 27 to closed clutch position, wherefore the drum 32 commences to be power rotated, exerting a pull on the draw band 36.

The line-spacing mechanism 39 and the carriage 10 afford considerable initial resistance respectively to operation and return and, therefore, the tension on the draw band 36 increases suddenly and violently as the load is being taken up, that is before the line spacing device starts to operate and again before the carriage is picked up. To suppress premature operation of the carriage return shut-off lever 66 through the sudden increase of tension on said draw band tending to straighten the stretch of band between the idler sheave 44 and the guide roll 46, there is provided a means comprising a latch 78, see Figure 1, which under carriage control blocks the shut-off lever 66 against operation at all times except when the carriage reaches fully returned position. Said latch 78 is in the form of a lever having a stationary pivot at 80. A member 81 linked to the latch 78 and having a sliding support at 82 in the housing 16 has a pin-and-slot connection at 83 with the arm 21 which has been said to constitute part of a counterstop means. A light spring 84 urges the member 81 leftwardly and thereby causes the arm 21 normally to occupy the left limit in the perforation 22, while maintaining the latch 78 resiliently in the return shut-off blocking position, all as illustrated in Figure 1. At the very last part of the return movement of the carriage, as illustrated in Figure 3, the margin stop 19 displaces the arm 21 rightwardly and consequently the latch 78 is swung clear of the return shut-off lever 66, 67. Since the resistance of the spring 84 and the resistance of the latch to movement is light, flexure of the parts 21, 81 and 78 is so negligible as not to affect proper and exact control of the latch 78 by the carriage over a very small movement of the carriage. Thus a fraction of a letter space before the carriage arrives in the fully returned position, the return shut-off lever becomes freed for operation, wherefore then the draw band 36 under the reliable power of the motor drive by a straightening action of the band effectively exerts upward pressure on the pulley 45 to actuate the return shut-off lever 66, 67 clockwise as seen in Figure 3. The roller 68 on the shut-off lever 66, 67 in such action descends down on the control arm 40 to restore it to open-clutch position, to be held by the latch 43 if the carriage return key 75 has meanwhile been released, or to be held temporarily by a substitute latch 43a seen in Figure 4 if the return key 75 is still held operated. The two latches 43 and 43a are independently pivoted on a common pivot stud, and a spring 86 connects them resiliently as shown in Figure 4, in oppositely bearing relation to the pin 76 on the carriage return lever 75. At operation of the latch 43 by the key 75 the latch 43a bears idly rearwardly against the control arm 40 under the tension of the spring 86. When the return shut-off takes place, the control arm 40 receives a power shut-off motion or impulse which carries it far enough for one or the other latch 43, 43a to spring thereover, depending on whether the carriage return key 75 has been released or not, but always when the return shut-off operation has taken place and the return key 75

75 is released the latch 43 will hold the arm against clutch closure.

It will be evident that at all line-spacing and carriage returning operations the load is picked up with the latch 78 in effective position. Moreover, in view of the latch 78 and the manner of control thereof, the clutch opening action can take place only if the carriage reaches very nearly the return limit position. Because of this the resistance against operation of the shut-off lever can be kept to a minimum, and the shut-off action in view thereof takes place with ease, a minimum of strain, friction and shock to the parts. This also reduces noise and the draw band in the embodiment of the invention shown is subjected to a minimum of strain and wear.

The clutch members 25 and 27 and the draw band drum 32 with related parts, are contained in a casing, not shown, and from such casing rises upwardly a bracket 87 which gives support to the pivot pins 69 and 80, as well as to the stop pin 72 and the pulley 44.

The machine of the invention may embody a tabulating mechanism such as shown in the patent to Helmond, No. 2,303,878, dated December 1, 1942 and including a tabulator reed indicated at 88 which upon projection moves slightly rightwardly to a latched position, to be released subsequently for spring restoration by the movement of a tabulator stop thereagainst. If a tabulating run is interrupted by the margin stop 18 running against and displacing the counterstop 20, then the tabulator reed 88 is unlatched automatically by a pin 90 on the counterstop arm 20 which displaces the reed 88 leftwardly, in a manner conventional in the marketed Underwood All Electric typewriters.

Having explained the nature and objects of the invention, and having specifically described a machine embodying the invention in its preferred form, what is claimed is:

1. In a business machine having a returnable carriage; a normally disabled power-return means for the carriage, means to enable said power-return means, means comprising a part of the power-return means, to tend to disable the power-return means after the latter has been enabled, and means including a control element on the carriage to incapacitate said tending means until the carriage in its power return reaches a certain position.

2. In a business machine having a carriage returnable on a frame; a normally disabled power-return means for the carriage, means to enable said power-return means, means comprising a part of the power-return means to tend to disable the power-return means after the latter has been enabled, and means to incapacitate said tending means until the carriage in its power return reaches a certain position, said last means comprising an element on the carriage and an element on the frame operable by the first said element as the carriage reaches the said certain position.

3. In a business machine having a returnable carriage and return limiting means for the carriage; normally disabled power-return means for the carriage, means to enable said power-return means, means comprising a part of said power-return means, to tend to disable the power-return means during its enablement, and carriage-controlled means to incapacitate said tending means until the carriage is power-returned substantially to the limit provided by the said limiting means.

4. In a business machine having a returnable carriage; a member displaced at the conclusion of each return-run of the carriage, normally disabled power-return means for the carriage, means to enable and to disable said power-return means, comprising a part of said power-return means tending to exert a disabling influence on the latter during its enablement, and means controlled by said member to suppress disablement of the power-return means by said tending means in each power-return of the carriage until said member has been displaced.

5. In a business machine having a returnable carriage; normally disabled power-return means for the carriage, and means to enable and to disable said power-return means, comprising a device which after enablement of the power-return means is positioned for operation to disable said power-return means, means cooperative with said device and including a part of said power-return means to tend, while the latter is enabled, to operate said device, and carriage controlled means to block operation of said device except when the carriage in its return movement reaches a certain position.

6. In a business machine having a returnable carriage and carriage return-limiting means for the carriage; normally disabled power-return means for the carriage, including a carriage-return draw band, means to enable said power-return means, an element arranged for displacement by a straightening pull on said draw band exerted during enablement of the power-return means, means to disable said power-return means by the displacement of said element, and carriage controlled means to suppress displacement of said element at all times except when the carriage reaches the returned position defined by said return-limiting means.

7. In a business machine having a limitedly returnable carriage, normally disabled power-return means for the carriage, including a carriage return draw band, means to enable said power-return means, an element arranged for displacement by a straightening pull on said draw band exerted during enablement of the power-return means, means to disable said power-return means by the displacement of said element, a member displaced at the conclusion of the limited return of the carriage, and means controlled by said member to delay operation of said element by said draw band until the carriage reaches the returned position.

8. In a business machine having a returnable carriage; a carriage return drive including a carriage return draw band and a normally open clutch, means to close and to open said clutch, thereby respectively to enable and disable said return drive, said last means including an element associated with the draw band, operable from one to another position to open said clutch, guide means for said draw band arranged relatively to said element for the draw band to exert an impositive power operating force on said operable element while said clutch is closed, and carriage controlled means to block said operable element against operation by said draw band until the carriage in its return movement reaches a certain position.

9. In a business machine having a returnable carriage; a normally disabled power-return drive for said carriage, means to enable and to disable said return drive, comprising, carriage return shut-off means normally in an idle position, spring means biasing said shut-off means to idle

position, means including a control element on the carriage to block said shut-off means against operation until the carriage in its return run reaches a certain position, and means including a part of the power-return drive tending to power-operate said return shut-off means in opposition to said spring whenever said return drive is active wherefore upon arrival of the carriage at said certain position said shut-off means is automatically power-actuated.

10. The combination with a business machine having a letter-feed carriage, a limitedly operable line-spacing device on the carriage, and carriage return limiting means including a carriage return limiting margin stop, arranged to permit in any letter-feed position of the carriage short thereof at least some carriage movement in return direction; of normally disabled power means having a connection with the line-spacing device to operate it first and then to propel the carriage for return to the limit provided by the return limiting means, and means to enable and to disable said power means comprising means to tend to disable said power means during enablement thereof, and means controlled by said margin stop to suppress disablement of said power means by said tending means until the carriage after actuation of the line-spacing device has been power propelled substantially to the position defined by the return limiting margin stop, wherefore then the power means is automatically disabled by said tending means.

11. The combination with a business machine having a letter-feed carriage and a limitedly operable line-spacing device on the carriage; of power means including a motor-operable normally open clutch and a draw band having a connection with said line-spacing device and being operable by said clutch when closed to operate first said line-spacing device and then to propel the carriage in a return direction, and means to open and close said clutch comprising means to tend to open said clutch by a straightening action of said draw band while the clutch is closed, and carriage controlled means to incapacitate said tending means pending the propelling of the carriage in said return direction beyond an initial letter-feed position, the carriage advancing to such position after it has ceased to be propelled in return direction.

12. In a business machine having a returnable carriage and return limiting means for the carriage; a normally disabled power-return drive including a normally open clutch, spring means biasing said clutch to close, releasable latch means normally holding said clutch open in opposition to said spring means, said clutch closing at release of said latch means, means urged by said carriage return drive during activeness thereof to open said clutch in opposition to said spring means, and carriage controlled means to delay operation of said urging means until the power-return drive has moved the carriage substantially to a position defined by the return limiting means.
